UNITED STATES PATENT OFFICE

ERNEST E. SCOTT AND ELMER H. BRIDENBAUGH, OF DENVER, COLORADO, ASSIGNEES
TO THE ELECTRIC ALARM CO., INC., OF DENVER, COLORADO, A CORPORATION OF
COLORADO

ELECTRIC ALARM DEVICE

Application filed April 30, 1928. Serial No. 274,186.

This invention relates to improvements in automatic alarms and has reference more particularly to an alarm mechanism which can be applied to automobiles and which will automatically sound an alarm whenever the automobile is disturbed.

It frequently happens that when automobiles are parked along the streets or highways that unauthorized persons will approach them and remove tires or accessories and will sometimes even steal the automobile itself, and unless the automobile is equipped with some alarm device, it is possible for thieves to take their time in performing their operations and in which case they may even circumvent the ordinary automobile locks so that the automobile can be removed under its own power.

It is a further object of this invention to produce an automatic signal that will be adapted for universal use and which, in addition to being applied to automobiles can also be used for the protection of houses, garages, stores or any other building where it is desirable to have a signal that will operate whenever an unauthorized person attempts to enter the building.

The above and other objects which will become apparent as the description proceeds, are attained by means of an apparatus which, briefly described, consists of a spring motor that is held in inoperative position by means of a detent which will be released by the action of an electromagnet whenever the device is subjected to vibration. After the motor has been released, it will be permitted to rotate a predetermined amount and during this rotation a mechanism operated by the motor will open and close a switch which can be attached to an automobile horn or in any other suitable signal. If the disturbance has ceased when the device has operated for the predetermined time, it will remain silent but will immediately resume its operation whenever it is again disturbed.

Having thus briefly described the invention, the same will now be described in detail and reference for this purpose will be had to the accompanying drawings in which

the preferred embodiment thereof has been illustrated and in which:

Fig. 1 is a side elevation of the improved signal showing the same within a casing from which the cover has been removed;

Fig. 2 is a view looking in the direction of arrow 2, in Fig. 1, showing one edge of the apparatus, the casing having been removed;

Fig. 3 is a view similar to that shown in Fig. 2, but looking in the direction of arrow 3, Fig. 1;

Fig. 4 is a view of the opposite side from that shown in Fig. 1, the casing having been removed;

Fig. 5 is a section taken on line 5—5, Figs. 1 and 4; and

Fig. 6 is a diagrammatic representation of the apparatus.

In the drawings numeral 1 represents a casing in which the apparatus is enclosed. This casing has sides 2 and 3 to which reference will be made hereinafter but as this casing merely forms a housing for the mechanism it will not be described in detail.

The mechanism to which this invention relates comprises two members 4 and 5, of insulating material such as hard rubber or a phenolic condensation product. Attached to opposite sides of members 4 and 5 are metal frames 6 and 7, which are alike in size and shape except for this, that frame 7 has a projection 8 (Fig. 1) which forms a support for the pivot 9 on which is mounted a bell crank lever having arms 10 and 11, whose function and mode of operation will hereinafter be described. Frames 6 and 7 are connected to each other and to the insulating members 4 and 5 by means of screws 12 and 13. A third frame member 14 is secured to frame 7 by means of screws 15 and spacers 16. An arbor 17 extends through all three frames 6, 7 and 14 and is journaled in bearings 18, one end of this arbor has a threaded portion 19 to which a winding key 20 is attached. The other end of arbor 19 has secured to it a ratchet wheel 21 with which a pawl 22 cooperates, a spring 23 keeps the pawl in engagement with the ratchet wheel. Mounted on arbor 19 between frame members 7 and 14 is a spring housing 24 containing a spring 25

of the type ordinarily employed in connection with clock mechanisms, one end of this spring is attached to the casing at 26 and the other end is secured to the shaft by means of a pin 27. When spring 25 is tensioned, it tends to rotate the casing 24 in the direction of the arrow in Fig. 6. Casing 24 has one side provided with teeth 28 that engage with the pinion 29 on shaft 30. This shaft is journaled in frame members 6 and 14 and passes through an opening in frame 7. Secured to shaft 30 are a ratchet wheel 31 and a gear wheel 32. Located adjacent the ratchet wheel 31, is a member having two arms 33 that are nonrotatably secured to shaft 30. A lever 34 has two angularly related arms 35 and 36 and is provided with a slot 37 through which the pivot pin 38 extends. A lug 39 extends from lever 34 and to the outer end of this projection one end of coil spring 40 is connected; the other end of this spring is anchored to pin 41. A stop 42 is secured to frame member 7 and serves to limit the rotation of lever 42 about the pivot 38. The lower end of arm 35 is provided with a projection 43 whose inclined edge is substantially parallel with the arm 36 and with the axis of slot 37. The upper end of arm 36 has an integral lug 44 to which the lower end of spring 45 is attached. The spring 40 normally holds the lever 34 in such a position that the upper end of arm 36 will be engaged by the arms 33 and to form a stop for the latter.

Secured to the insulating member 5 is a solenoid 46 with which is associated a core 47. Secured to the outer end of core 47 is a metal strap 48 whose end is provided with a slot 49 through which the end 50 of arm 35 extends. When the electromagnet or solenoid is energized by an electric current, the core 47 will be moved towards the right (Fig. 1) and this will rotate lever 34 about its pivot 38 so as to remove the upper end of arm 36 from in front of the arm 33 and thereby permit shaft 30 to be rotated by the spring 25. When the arm 33 has been released shaft 30 and ratchet wheel 31 will rotate through one hundred eighty degrees when the other arm 33 will engage the end of lever 36. A pawl having angularly related arms 10 and 11 is pivoted at 9 and has the end of arm 10 provided with a tooth 51 which engages with the teeth on the ratchet wheel in the manner shown in Fig. 1. The free end of arm 11 has a roller 52 that is engaged by the spring 53 whose upper end is secured to the bracket 54. Spring 53 tends to rotate the pawl in such a direction that the tooth 51 will always rest against the periphery of wheel 31. When ratchet wheel 31 rotates the pawl, pivoted at 9, will oscillate and vibrate the spring 53, whose end carries a contact 55 which will thereby be moved into engagement with the stationary contact 56 on the bracket 57. Con-

tacts 55 and 56 form a signal control switch to which reference will be made hereinafter. Gear wheel 32 meshes with a pinion 58 on shaft 59 which also carries a large gear 60 that in turn engages a pinion 61 on shaft 62 to which the disk 63 is attached. Gears 32, 58, 60 and 61 form a train which act as a retarder for limiting the speed of rotation of shaft 30.

The solenoid or electromagnet 46 has one end of its energizing coil grounded at 64 and the other end connected to the bracket 65 by means of a strip 66 of conducting material. Bracket 65 has a base 67 and a parallel end or top part 68 and is fastened securely to the insulating block 4 by means of screws 60. A pivot 70 is secured to base 67 and a pointed screw 71 is threadedly connected with the end 68 and held against rotation by means of a nut 72. A block 73 is mounted between the pivots 70 and 71 and this has secured to it a spring 74 to which is connected a weight or inertial member 75 that can be moved along this spring and is held in adjusted position by means of a screw 76. The free end of spring 74 carries a contact 77 that is normally separated from contact 78 that is carried by bracket 79. A short spring 80 has one end attached to the block 73 and has its free end engaged by the end of the adjusting screw 81. By means of the screw 81 the parts can be so adjusted that when the device is undisturbed, contacts 77 and 78 will be separated, but when the device is disturbed contacts 77 and 78 will move together.

From Fig. 6 it will be seen that bracket 79 is connected to one terminal of the battery 82 whose other terminal is grounded at 83 and therefore whenever contacts 77 and 78 come together, an electric current will flow from the battery through the spring 74 and conductor 66 to the solenoid coil and to ground 64, thereby energizing the electromagnet and releasing arm 33 so as to permit shaft 30 to rotate in the manner above explained. As soon as arm 33 has been released, spring 40 will move lever 34 upwardly to the limit of the slot 37 and thereby bring the upper end of spring 45 into contact with the under surface of spring 74 and hold the latter from flexing and thereby prevent the reestablishment of electrical connection between contacts 77 and 78 until the other arm 33 has been rotated into such a position that it engages the end of lever 36 and moves it downwardly against the action of spring 40 to the position shown in Fig. 6. From Fig. 6 it will also appear that bracket 54 is connected with the ungrounded terminal of the battery by means of conductors 84 and 85 and that a conductor 86 connects bracket 57 with a signal horn 87 that is grounded at 88. When the ratchet wheel 31 is rotated contacts 55 and 56 will be moved into contact and separated, thereby alternately making and breaking the

current to the horn 87 which will therefore emit a series of sounds. If the initial disturbance ceases the shaft 30 will make one-half a revolution only and will then come to rest, but if the device is disturbed when arm 33 has engaged the upper end of lever 36, the vibrations will cause the theft protective switch contacts 77 and 78 to again come into contact and as soon as this occurs, the electromagnet will function and remove the stop and thereby release the arms 33 so that the parts will function and repeat the alarm.

Although this signal is primarily intended for use on automobiles, it is equally well adapted for use as a burglar alarm for buildings and if attached to a safe will sound an alarm if the latter is disturbed.

In the embodiment illustrated, the device is operated by a spring motor but it may be operated by any other form of motor and especially by means of an electric motor, and the specific motor shown should therefore be considered as illustrative of means only.

Having described the invention what is claimed as new is:

1. A theft alarm device comprising, in combination, a supporting frame, a spring motor carried by the frame, said motor having a gear wheel, a shaft mounted for rotation in the frame, a gear carried by the shaft, said gear being in mesh with the gear on the motor, a signal control switch, means for opening and for closing the signal control switch when the shaft rotates a radial arm carried by the shaft, a pivot pin secured to the frame, a stop lever provided with an elongated opening through which the pivot pin extends, one end of said lever when in one position lying in the path of the arm and adapted to be engaged thereby to form a stop for holding the shaft against rotation whereby the signal control switch will be held against movement, a stop carried by the frame for limiting the movement of the lever in one direction, a spring having one end secured to the lever at one side of the opening and the other end secured to the frame at a point located between the pivot point and the end of the lever whereby a force component is produced which tends to move the lever in the direction of its length and a torque is produced which tends to rotate the lever about its pivot into engagement with the stop, means comprising an electromagnet and an armature for moving the lever to inoperative position, a theft protective switch in series with the magnet, and a spring secured to one end of the stop lever and adapted to engage the theft protective switch to hold the latter in open position while the shaft is rotated.

2. A theft alarm device comprising, in combination, a supporting frame, a spring motor carried by the frame, said motor having a gear wheel, a shaft mounted for rotation

in the frame, a gear carried by the shaft, said gear being in mesh with the gear on the motor, a signal control switch, means for opening and closing the signal control switch when the shaft rotates, said means including a cam member carried by the shaft, a radial arm carried by the shaft, a pivot pin secured to the frame, a stop lever provided with an elongated opening through which the pivot pin extends, one end of said lever when in one position lying in the path of the arm and adapted to be engaged thereby to form a stop for holding the shaft against rotation whereby the signal control switch will be held against movement, a stop carried by the frame for limiting the movement of the lever in one direction, a spring having one end secured to the lever at one side of the opening and the other end secured to the frame at a point located between the pivot point and the end of the lever whereby a force component is produced which tends to move the lever in the direction of its length and a torque is produced which tends to rotate the lever about its pivot into engagement with the stop, means comprising an electromagnet and an armature for moving the lever to inoperative position, a theft protective switch in series with the magnet, and a spring secured to one end of the stop lever and adapted to engage the theft protective switch to hold the latter in open position while the shaft is rotated.

In testimony whereof we affix our signatures.

ERNEST E. SCOTT.
